UNITED STATES PATENT OFFICE

FRIEDRICH H. M. POHL, OF WOODCLIFF, NEW JERSEY, ASSIGNOR TO CO-OPERATIVE EMBROIDERY COMPANY, OF WOODCLIFF, NEW JERSEY, A COPARTNERSHIP CONSISTING OF FRIEDRICH H. M. POHL AND ENO MAEDLER

DESIGN FOR AN EMBROIDERED TEXTILE FABRIC OR SIMILAR ARTICLE

Application filed July 29, 1932. Serial No. 44,479. Term of patent 3½ years.

To all whom it may concern:

Be it known that I, FRIEDRICH H. M. POHL, a citizen of the United States, residing at 1141 Third Avenue, Woodcliff, county of Hudson, State of New Jersey, have invented a new, original, and ornamental Design for an Embroidered Textile Fabric or Similar Article, of which the following is a specification, reference being had to the accompanying drawing, forming part thereof.

The figure is a plan view of an emboid-ered textile fabric or similar article, showing my new design.

The dot and dash lines in the drawing outline the design unit, which unit is repeated in regular succession, as indicated by the extensions beyond the unit boundaries.

I claim:

The ornamental design for an embroidered textile fabric or similar article substantially as shown and described.

FRIEDRICH H. M. POHL.
